UNITED STATES PATENT OFFICE

114,263

DESIGN FOR A BELT BUCKLE

Amson Furtsch, New York, N. Y.

Application January 27, 1939, Serial No. 82,633

Term of patent 3½ years

To all whom it may concern:

Be it known that I, Amson Furtsch, a citizen of the United States, residing in the Borough of Manhattan, city, county, and State of New York, have invented a new, original, and ornamental Design for a Belt Buckle, of which the following is a specification, reference being had to the accompanying drawing, forming a part thereof, in which:

Fig. 1 is a top view of a belt buckle made in accordance with the present design;

Fig. 2 is a front elevational view thereof;

Fig. 3 is a side view thereof;

Fig. 4 is a cross-sectional view taken along the line 4—4 of Fig. 2; and

Fig. 5 is a horizontal cross-sectional view taken along the line 5—5 of Fig. 2.

The characteristics features of the present design reside in a curved, elongated, rectangular plate which is relatively thin, having along the four sides thereof a raised bead of relatively heavy cross-section. Three rectangular openings are provided in the plate, two of them being adjacent to the opposite ends thereof and the third one being adjacent to one of said first-mentioned openings.

I claim:

The ornamental design for a belt buckle, substantially as shown and described.

AMSON FURTSCH.
